MESNE ASSIGNMENTS, TO STEEL AND TUBES, INC., OF CLEVELAND, OHIO, A COR-
PORATION OF OHIO

PEDESTAL BENDING MACHINE

Application filed May 13, 1928. Serial No. 108,835.

This invention relates to the art of bending metallic articles, and is especially concerned with the construction of new and improved apparatus for bending elongated metallic articles, particularly pipe, which may be constructed at relatively low expense and which is simple and easy to operate and is, to a certain extent, automatic in operation.

A chief object is to provide an apparatus which will bend light gauge tubing without substantial reduction in area, formation of wrinkles or other marks of objectionable character.

A further object is to provide apparatus for bending a metallic article, particularly a tube, into a plurality of planes.

Other objects will appear and be pointed out hereinafter.

In the drawings attached to and forming a part of this application—

Fig. 1 is a top plan view of one form of apparatus embodying my invention;

Fig. 2 is a front side elevation of the apparatus of Fig. 1;

Fig. 3 is an end elevation taken in the direction indicated by line 3—3 of Fig. 1;

Fig. 4 is a longitudinal section of a valve piston; and

Fig. 5 is a fragmentary top plan view showing the bending roll and follower shoe assembled with the adjacent parts of the machine.

In the drawings in which we have illustrated one form of our invention, 1 designates a hollow base comprising a circular housing having an offset extension 2. On top of the base 1 is mounted a pedestal 3 which tapers upwardly to small dimensions and which carries near its upper end a laterally extending, narrow bed 4 supported at its outer end by a leg 5. A bending roll shaft 6 extends in an upright position through the pedestal 3 and is supported on the top of the bed 4 by an outstanding annular flange 7 which rests upon a suitably

flanged bushing 8, the lower end of the shaft 6 being provided with a suitable bushing 9 supported in a bearing socket 10 carried by the base 1. This socket 10 may conveniently be carried by a cross wall 11 of the housing 1 and provides a bearing face to support a ring gear 12 keyed to the shaft 6. This gear 12 meshes with a worm gear 13 rotatably mounted in the offset projection 2 of the housing 1. A drive shaft 15 is keyed to the worm gear 13 and communicates with two oppositely driven drive pulleys 16 and 17 which normally rotate relative to the shaft 15 but which may be engaged to drive the latter by means of a clutch 18 actuated by a clutch lever 19 and a clutch shaft 20. The actuation of the shaft 20 will presently be described in more detail.

The bending roll shaft 6 carries near its upper end a collar 21 clamped about a collar on the shaft 6 so as to rotate therewith. This collar 21 is slit circumferentially as at 22 and two similar dogs 23^a and 23^b are adjustably secured in the slit 22 so as to engage with a lever 24 presently to be described.

A suitable bending roll A is keyed to the shaft 6 above the collar 21 and is of such size as to cooperate with follower shoe B which is backed by a keeper roll 25 rotatably mounted on a carriage or bracket 26 which bracket is mounted to slide between guides 27 on the top of the bed 4 toward and away from the shaft 6 and its bending roll. A roller C is secured to roll A as shown in Fig. 5 in position to clamp a tube or article to be bent to the roll when shoe B is brought to its operating position by roll 25. The tube or other article is first inserted between roll A and roller C, then shoe B is placed between the article and roll 25. When roll 25 is moved toward roll A, the article is secured to roll A so as to rotate with it. A pair of eye-bolts 28 and a turnbuckle 29 serve to connect the bracket 26 with a crank arm 30 keyed to a shaft 31 which extends down through

the bed 4. The shaft 31 carries at its lower end a crank arm 32. A connecting rod 33 is fastened at one end to the crank arm 32 and at the other end to a piston 34 reciprocably mounted in a cylinder 35 carried on the underside of the bed 4.

Means for actuating the roll 25 to its normal position is shown in the spring 36 while means for actuating it in the opposite direction comprises fluid pressure means conducted to the cylinder 35 through pipe 37 and a valve 38. Valve 38 is carried by the bed 4 and as shown comprises a cylinder within which is slidably mounted a circular valve 15 piston 39 connected to a rod 40' which extends out through the end of the valve cylinder 38 and is connected to a hand lever 40. An intake pipe 41 brings fluid under pressure, for example compressed air, into the cylinder 38 where, when the piston 39 is properly positioned, it may pass through annular grooves in the cylinder liner 42, thence into a recess 43 on the piston and out through the pipe 37 into the cylinder 35. When the 25 piston 39 is moved so that the piston closes the inlet opening and connects the opening from pipe 37 with the outlet 37', the pressure in the cylinder 35 is relieved and the spring 36 is capable of retracting the bracket 26 to 30 the position shown in Fig. 1. It will be understood that the movement of the piston 34 results in a movement of the bracket 26 and the rotatably carried roll 25 toward the shaft 6 and any bending roll carried thereon.

35 A second cylinder 44, similar in substantially all respects to cylinder 38, may also be carried on the side of the bed 4 in a position similar to and closely adjacent to the cylinder 38. This cylinder is constructed 40 with a sleeve, corresponding to the sleeve 42 of cylinder 38, and with a piston similar to the piston 39. A connecting rod 45, similar in substantially all respects to the connecting rod 40', is secured to the piston within the cylinder 44 and extends through one end of the cylinder to engage with a coupling 46 which is secured pivotally to the lever 24, heretofore mentioned. This lever is pivoted 45 near its lower end on a pin carried by the pedestal 3. The movement of the lever 24 about this pivotal point carries with it the rod 45 and moves the piston within the cylinder 44 first in a position to uncover and connect the inlet pipe 47 and the outlet pipe 55 48 which leads to a cylinder 49 mounted on the pedestal of base member 1. Fluid pressure in the cylinder 49 or pipe 48 is exhausted through opening 49a in the cylinder 44 when the piston in the cylinder 44 is moved into 60 suitable position, in substantially the same manner as has been just described in connection with cylinder 38 and piston 39.

Within the cylinder 49 a piston 49a is reciprocably mounted and carries, at its end opposite to the end where the pipe 48 enters,

a connecting rod which is adjustably connected to the clutch-shifter shaft 20 by a turnbuckle 51. The connecting rod has a bearing in a bracket 52 which comprises a part of the cylinder assembly. Between the piston and the bracket 52 and surrounding the connecting rod is disposed a spring 53 capable of returning the piston within the cylinder to the end of the latter adjacent to the entrance of pipe 48 when the fluid pressure within the cylinder is relieved.

Movement of the piston in cylinder 49 back and forth serves to move the clutch-shifter 20 similarly and to engage or disengage the clutch 18 with the drive pulleys 16 and 17.

The connecting rod is provided with a pin extending therethrough and indicated by character 54. This pin projects through elongated openings 54a in the forked end of a lever 54b keyed to a quadrant shaft 55. This quadrant shaft 55 extends across and is supported on the lower portion of the pedestal 3 by a bearing at either end and carries at the front side of the machine a release lever 56 keyed to the shaft 55. This lever 56 carries a dog 57 and a handle 58 for operating the same, the dog being disposed to engage with a quadrant 59 which has a stop 60. The quadrant as shown is supported by suitable legs 61 on the pedestal 3. The elongated holes 54a in lever 54b permit the shaft 55 to be rotated by the lever 56 and to move the shaft 20 back and forth so as to engage or disengage the clutch 18 with the drive pulleys 16 and 17.

The operation of the machine above described is substantially as follows: An elongated metallic article to be bent is secured in position between a suitable bending roll on shaft 6 and follower shoe supported by the holding roll 25 on bracket 26, the hand lever 40 then being actuated to permit fluid under pressure to be delivered into the cylinder 35 forcing out the piston and connecting rod 33, thereby turning the shaft 31 and moving the bracket 26 into holding position with respect to the article to be bent. If desired the piston 39 may be moved into position to lock the pressure in the cylinder 35, as by closing the intake opening from pipe 41. When the article to be bent has been fixed between the bending roll and the holding roll 25, the machine is ready to be actuated. The lever 56 is then moved to the left by elevating the dog 57 out of contact with the stop 60, thereby moving the clutch shaft 20 to the left of the apparatus shown in Fig. 2, thereby engaging the clutch 18 with the drive pulley 16, this rotates the drive shaft 15 and the worm 13 turns the worm wheel 12 and with the latter the bending roll shaft 6. This rotation continues until the dog 23a engages with the end of the lever 24 and moves the latter about its pivot to shift the piston in cylinder 44 so

as to admit compressed air from pipe 47 and discharge it through pipe 48 into the cylinder 49 where it forces the piston outwardly in the cylinder compressing the spring 53 and moving the shaft 20, thereby disengaging the clutch 18 and drive pulley 16 and then bringing the clutch 18 into engagement with the drive pulley 17. This movement of the clutch shifter 20 carries with it the lever 56 to the extreme end of the quadrant 59. The drive pulley 17 rotates the shaft 15 in the opposite direction thereby returning the shaft 6 to its initial position where the dog 23 contacts with the lever 24 moving it in the opposite direction about its pivot and moving the piston in cylinder 44 so as to connect the pipe 48 with the discharge outlet 50, thereby relieving pressure in the cylinder 49. When the pressure in the cylinder 49 and against the piston therein is thus relieved, the spring 53 is permitted to function and serves to move the clutch shifter shaft 20 to disengage the clutch 18 and drive pulley 17, this movement being accompanied by a corresponding movement of the lever 56 which movement is stopped or intercepted by the stop 60 on the quadrant 59 with which the dog 57 engages.

It is preferable that the lever 40 be moved so that pressure from the cylinder 38 may be relieved through outlet 43 at about the time the shaft 6 ceases rotating in its initial direction and begins reversed rotation to restore it to its original position. When this is done the bent article may be removed from between the bending roll on the shaft 6 and the holding roll 25 and taken to the truck or other place of disposal for the bent articles. Another article to be bent can be procured during the time the shaft 6 is being rotated to its initial position so that when the lever 56 has been stopped by the dog 57 engaging the stop 60 and the machine has ceased operating, the second article will be in position to be gripped between the bending roll and the holding roll 25, and the above described operation again repeated.

It will be understood from the foregoing description that the operation of the machine just described is extremely easy to perform, is not fatiguing to the operator and does not require the manipulation of many levers or other devices at any time or of any levers at the time when the operator should be giving some attention to the articles being bent. For example, only one lever, namely, lever 40, needs to be actuated prior to the time the articles to be bent are gripped against the bending roll. After the article is gripped in bending position only one other lever needs to be actuated, this being lever 56, after which the operation of the machine is naturally automatic until the lever 40 is to be actuated to release the work blank. The entire operation is therefore, semi-automatic.

It will also be readily apparent to those

skilled in the art from the foregoing description of the apparatus that we have constructed an apparatus which is extremely easy to make because of the form, size and feature of the parts comprising the apparatus, which is compact and which does not require very much floor space,—all as contrasted with bending machines used prior to our invention.

It will also be evident to those skilled in the art that we have provided a supporting means for the bending roll and follower shoe which is of relatively small area and size adjacent to the roll and follower as a result of which it is possible to make a wide variation of sizes and varieties of bends. For example, a bend can be made in one plane followed by a bend of up to or in excess of 180° in another plane without obstruction being offered by the roll support.

Although various changes, alterations and modifications in the foregoing apparatus may be suggested by those skilled in the art without involving invention, all such changes, alterations and additions fall within the scope and spirit of our invention. The scope of our invention is defined in what is claimed.

What is claimed is:

1. A bending machine comprising a rotatable bending roll, a holding member having a supporting roll associated therewith, said holding member and roll being movable toward and away from the bending roll in a direction radial of the latter, means for actuating the holding member toward the bending roll, means for automatically moving the holding member away from the bending roll when the last said means is in released position, and means including a starting lever for rotating, reversing and finally stopping the bending roll.

2. A bending machine comprising a rotatable bending roll, a holding member and a supporting means therefor, said member and supporting means being movable toward and away from the bending roll radially of the latter, pneumatic means for actuating the holding member toward the bending roll, and means including a starting lever for rotating the bending roll a predetermined distance, reversing the direction of rotation and stopping the roll in its initial position.

3. A bending machine comprising a rotatable bending roll, a holding member and a supporting roll therefor, said holding member and roll being movable toward and away from the bending roll, pneumatic means for actuating the holding member toward and maintaining it in operative position with respect to said bending roll, and means including a starting lever for rotating the bending roll predetermined distances in one direction and then in the opposite direction.

4. A bending machine comprising a pedestal, an upright bending roll shaft therein, a bending roll on the shaft, a bed extending

- laterally from the pedestal, a holding roll movably mounted on the bed, fluid pressure means operatively associated with the said roll, means on the bed actuatable by the fluid pressure means to move the bending roll into article gripping position and means for rotating the said shaft.
5. A bending machine comprising a pedestal having therein an upright bending-roll shaft, a drive gear in the lower portion of the pedestal and on the said shaft, a bed extending laterally from the pedestal and carrying a movable holding roll, a bending roll on the shaft rotatable above the top of the said bed, means to rotate the shaft, two oppositely rotating drive pulleys, clutch means engageable with one of the pulleys to rotate the shaft and automatic means for disengaging the clutch from one pulley and 20 engaging it with the other pulley.
6. A bending machine comprising a pedestal having therein an upright bending-roll shaft provided with a drive gear disposed on its lower end and within the lower portion of the pedestal, a bending roll on the upper end of the said shaft, a bed extending laterally from the pedestal and carrying a movable holding roll, means to rotate the shaft, two oppositely rotating drive pulleys, clutch 25 means engageable with one of the pulleys to rotate the shaft and means to disengage the clutch means from said second pulley.
7. A bending machine comprising a pedestal having therein an upright bending-roll shaft, a bed extending laterally from the pedestal and carrying a movable holding roll, a bending roll on the shaft above the said bed, pneumatic means for moving the holding roll toward the bending roll, manually 30 controlled means for producing rotation of said shaft in one direction, automatically operable means for arresting the said rotation and reversing the rotation, and positive means to stop rotation of the shaft at its initial position.
8. A bending machine comprising a pedestal having an upright, rotatable bending roll shaft, means in the lower portion of the pedestal to rotate the shaft, a bending roll on the upper end of said shaft, a bed projecting laterally from one side of the pedestal below said bending roll, a gripping member movable on said bed toward and away from the roll, and means to actuate said member.
55. 9. A bending machine comprising a pedestal having an enlarged base and a relatively small top as compared therewith, an upright bending roll shaft rotatably mounted within the pedestal, a drive gear on the shaft within the enlarged base, a narrow bed of substantially the same width as the top of the pedestal extending laterally therefrom, a bending roll carried by the said shaft above the said bed, means carried by the bed for holding an article to be bent against the bending roll,

means for rotating the said bending roll shaft, and means for actuating the article holding means.

10. A pipe bending machine comprising a bending roll rotatable about a vertical axis, 70 means for rotating said roll, a single keeper roll freely rotatable about an axis parallel to that of the bending roll, means for varying the distance between said axes, along the line joining the centers of the rolls, and a 75 follower shoe movable endwise between a tube and the keeper roll and at right angles to the said center to center line.

11. A pipe bending machine comprising a rotatable bending roll, means for rotating 80 said roll, a keeper roll freely rotatable about an axis parallel to that of the bending roll, means for moving the axis of one roll relative to the other, and a follower shoe insertable between the keeper roll and a tube and disposed tangentially to the peripheries of both rolls at the intersections therewith of a line joining the centers of the rolls.

12. A pipe bending machine comprising a vertical pedestal having an enlarged base portion and a smaller top portion, an elongated bed of approximately the width of the said top portion extending horizontally from the top of the pedestal, a vertical shaft rotatably mounted in the pedestal, means in the said base portion for rotating the shaft, a bending roll on the shaft above the bed, means movable lengthwise of the bed into and out of operative position with respect to the bending roll, means, including fluid under pressure, for semi-automatically moving the last said means toward and away from the bending roll, and means, including fluid under pressure, for semi-automatically rotating and restoring the said shaft to its initial 100 position.

13. A pipe bending machine having a vertical pedestal housing, a vertical shaft, means in the base of the pedestal for rotating the shaft, a bed extending horizontally from the top of the pedestal, a bending roll on the shaft above and of a diameter at least substantially as great as the width of the bed, a keeper slidably lengthwise of the bed, fluid pressure means for moving the keeper toward the said roll including a piston, cylinder and control valve carried by the bed, spring means for retracting the said keeper, and means for rotating the said shaft.

14. A pipe bending machine having a vertical pedestal housing, a vertical shaft, means in the base of the pedestal for rotating the shaft, a bed extending horizontally from the top of the pedestal, a bending roll on the shaft above and of a diameter at least substantially as great as the width of the bed, a keeper slidably lengthwise of the bed, fluid pressure means for moving the keeper toward the said roll including a piston, cylinder and control valve, means for retracting the said 120 125 130

keeper, and means for rotating the said shaft.

15. A pipe bending machine having a vertical pedestal housing, a vertical shaft, means in the base of the pedestal for rotating the shaft, a bed extending horizontally from the top of the pedestal, a bending roll on the shaft above the bed, a keeper slidably lengthwise of the bed, means to move the keeper toward and away from the said roll, means for rotating said shaft including a clutch and a clutch control lever, and means for stopping, reversing and again stopping the rotation of said shaft including a cylinder, piston and control valve.

16. A pipe bending machine comprising a bending roll, manual means for causing rotation of the roll in one direction, automatic means for causing stoppage, reverse rotation and final stoppage of the said roll, including a fluid pressure cylinder and piston, a valve controlling the same and means for actuating the valve, a keeper and manual means for actuating the keeper to move the latter towards the bending roll.

17. A pipe bending machine comprising a bending roll, means for rotating the roll in either direction including selectively employed clutches, manually operable means for selecting one clutch thereby rotating the roll in one direction, means for selecting the other clutch thereby reversing the direction of rotation of the roll, including a fluid pressure cylinder and piston, a valve for controlling admission of fluid under pressure into said cylinder and valve actuating means controlled by said roll, a keeper, and means for actuating the keeper.

18. A pipe bending machine comprising a keeper, manual means for initially actuating the keeper, including a fluid pressure cylinder and piston, and a valve for controlling the same, a bending roll, manual means for initiating rotation of the roll, and automatically operable means for controlling the roll including a fluid pressure cylinder and piston and a valve for controlling the same.

19. A pipe bending machine comprising a keeper, means for actuating the keeper, including a fluid pressure cylinder and piston, and a valve for controlling the same, manual means for initially operating the valve and automatic means for subsequently operating the valve, a bending roll, means for rotating the roll, and means for controlling the roll including a fluid pressure cylinder and piston and a valve for controlling the same, the first said valve being connected with and serving also as a control for the second said valve, the latter having manually operable means associated therewith to initiate rotation of the bending roll.

20. A bending machine comprising in combination a bending roll, means for rotating the same for bending movement and for rotating it in the opposite direction, a holding

roll, fluid pressure means for actuating the holding roll toward the bending roll on the center to center line of the rolls to press an article to be bent against the bending roll, and means for automatically retracting the holding roll when the bending roll reaches the end of its bending movement and before the latter is rotated in the reverse direction.

In testimony whereof we hereunto affix our signatures this 11th day of April, 1926.

HARRY E. HARVEY.
EARL K. HOLMES.
